[57] **ABSTRACT**

A rotary tubular brush having a tubular core, said core having axially elongated tuft holes, and tufts secured in the holes by staples. The tuft holes may be formed by, for example, a machine that moves a rotary drill for drilling circular holes first downwardly and then upwardly while the core is moved axially. Also the tuft holes may be formed by burning, casting or punching. Additionally, brushes other than tubular brushes may have tuft holes for tufts that are of a greater cross-sectional dimension in one direction than the other in a plane perpendicular to the depth direction of the holes.

ELONGATED HOLE BRUSH

BACKGROUND OF THE INVENTION

A tubular brush having tufts secured in holes in the tube.

In prior art tubular brushes, for example, such as disclosed in U.S. Pat. No. 2,879,534 and U.S. Pat. No. 3,614,801, the tufts are mounted in circular holes having conical bottoms that extend radially relative the central axis of the brush. In U.S. Pat. No. 648,527 there is disclosed a rotary brush wherein the tuft holes are circular and inclined relative to the radius of the brush. In such prior art brushes a relatively large number of holes are required for mounting a given amount of tuft bristles. In order to reduce the number of tuft holes for mounting a given amount of bristles, to obtain other economies in manufacture and to provide other advantages, this invention has been made.

SUMMARY OF THE INVENTION

A tubular brush having tuft holes that are axially elongated.

One of the objects of this invention is to provide a brush having tuft holes of a new and novel shape. Another object of this invention is to provide a new and novel brush that requires a substantially smaller number of tuft holes to mount a given amount of tuft bristles than prior art brushes.

An additional object of this invention is to provide a brush having tuft holes that are elongated in a direction axially relative the brush core. In furtherance of the last mentioned object, it is another object to provide opposed side wall portions, which in part define the tuft holes, that generally converge in a radially inward direction.

BRIEF DESCRIPTION OF THE DRAWINGS

FIG. 1 is a side elevational view, partly sectioned along a longitudinal axis, of a representative tubular brush of this invention;

FIG. 2 is an end view of the brush of FIG. 1;

FIG. 3 is a fragmentary representation of the brush tube as though the tube were cut longitudinally and flattened; this view illustrating the outer surface of the brush tube after drilling and before tufting to show an exemplary pattern of location of tuft holes;

FIG. 4 is an enlarged view of a portion of FIG. 3 to more clearly show the tuft holes;

FIG. 5 is a fragmentary longitudinal cross-sectional view generally taken along the line and in the direction of the arrows 5-5 of FIG. 4;

FIG. 6 is a fragmentary transverse cross-sectional view generally taken along the line and in the direction of the arrows 6-6 of FIG. 5 other than it additionally shows a tuft stapled in place;

FIG. 7 is a fragmentary longitudinally cross-sectional view generally taken along the line and in the direction of the arrows 7-7 of FIG. 6; and

FIG. 8 is a schematic representation of a machine for forming elongated tuft holes in a tubular core to illustrate one method of forming such holes.

Referring to FIGS. 1-7, the tubular brush, generally designated 10, includes a tube 11 having a plurality of holes 12 in which tufts 13 are secured by staples 14. The tube may be made of a rigid foam thermoplastic material such as disclosed in the above mentioned U.S.

Pat. No. 3,614,801 or of impregnated paper such as disclosed in U.S. Pat. No. 2,879,534 or other suitable materials.

Provided in the tube throughout the length L are a plurality of tuft holes 12, the pattern of the holes and the hole depths (HD) advantageously being similar to that disclosed in U.S. Pat. No. 2,879,534. However, the shape of the holes is different. That is, each of the holes 12 extends generally radially from the outer surface of the brush and at the outer surface has an axial length X that is substantially greater than the transverse width D. Further, the holes are shaped such that lines 15, 16 at the intersection of a plane of both the central axis of the tube and the central axis CC of the hole with side wall surface portions defining a hole 12 from the generally conical bottom 12a of the hole outwardly diverge at an included angle D (see FIG. 5), while the lines 17, 18 of intersection of a plane of the central axis CC of the hole that is perpendicular to the central axis C of the tube with the side wall surface portions defining the hole are parallel to one another and to the central axis of the hole (see FIG. 6). It is preferred that the dimension X is about 40 percent greater or more than the dimension D. The side wall surface portions defining each hole from the conical bottom outwardly are smoothly, continuously curved.

A tube thickness TT of about 1/2 inch to 5/8 inch is satisfactory in most instances for a brush for scrubbing and sweeping purposes; although for larger diameter brushes and heavy duty brushes, the thickness may be increased to 1.0 inch or more. The hole depth is always less than the tube thickness to leave an underhole thickness UHT of a substantial dimension. Preferably the hole depth is greater than the transverse dimension D of the hole and about two-thirds of the tube thickness TT.

The tufts 13 are made of bristle suitable for the work to be done. Examples of suitable bristle material are set forth in U.S. Pat. 2,879,534. Further, the staples 14 for retaining (anchoring) the tufts in the holes and the manner of setting the staples is set forth in the last mentioned patent.

Other than for the surface portions defining each hole 12 that are closely adjacent the lines 17, 18 of intersection of the wall surfaces defining the hole with a plane of the center axis of the hole CC that is perpendicular to the center axis C of the tube, the lines of intersection of planes of the hole center axis C with the wall portions defining the hole outwardly of the conical bottom diverge. As a result the bristles are not as sharply bent and more bristles can be placed in each hole than in brushes having circular tuft holes. Additionally due to the bristles fanning outwardly from a location substantially inwardly of the outer surface of the tube, the normal axial spread (dimension Y) of the bristles at their outer ends is greater than that where circular holes of the same cross-sectional area are provided. Additionally it is preferred that the adjacent holes in each axial row of holes are sufficiently close that the bristles of tufts 13a, 13b in adjacent holes (see FIG. 7) overlap at their outer ends so that at least some of the bristles of one tuft have their outer ends located radially outwardly of the center part of the hole for the other tuft. This overlap closes any open space which would develop between tufts upon brush wear.

By using the axially elongated holes, there is obtained a flared fanned-out tuft. Further, the number of holes

per each axial row can be reduced by about 50 percent from that required for circular tuft holes and still provide the same amount of fill for each row. As a result the brush of this invention is less expensive to make.

Also, advantages of using axially elongated tuft holes such as described over full continuous slots that extend substantially the axial length of a brush which are filled with bristles are that more individual bristle action is obtained, less bristles are required, and overlapping tufts give an interrupted but complete pattern of action to provide more effective polishing, sweeping or scrubbing.

One manner of making the holes in tubular blank is to use a machine having a carriage 30 mounted on the frame 31 for reciprocal movement (see FIG. 8). The carriage mounts members 32 that in turn mount a tubular blank 36. A drill 33 for drilling a circular hole is mounted by the frame to be reciprocally moved perpendicular to the central axis of the tube blank, and is rotatably driven by suitable means (not shown). In 20 using this machine with the tubular blank mounted therein at one end of the reciprocally movement of carriage, the carriage is translated to move the tubular blank axially in one direction and at the same time the drill is continuously moved downwardly until the hole 25 is drilled to its maximum depth and then the drill is continuously moved upwardly until the hole is completed. The vertical reciprocal movement of the drill is cycled the number of times to complete the holes for a row.

Even though the above refers to drilling holes, it is to be understood the holes may be formed by molding, burning, casting or other methods, depending on the material that the tubular core is made from. Further, it is to be understood that the core need not be tubular 35 but may be a solid cylinder.

Additionally, flat brushes such as side sweep and scrub brushes that have a generally cylindrical, tuft mounting member normally rotated about the central axis thereof and have tufts extending outwardly of the generally flat surface thereof advantageously may have tuft holes provided in the mounting member that are of a shape previously described, i.e., are of increasing dimensions from adjacent the bottom of the holes to the outer ends thereof. With such side sweep and scrub 45 brushes, it is preferred that the direction of elongation of the tuft holes are generally radially relative said central axis.

As examples of the invention, the tubular brush of example (a) the tubular core may have a wall thickness 50 TT of 0.437 inches, a hole that at the outer surface of the tube is of an axial dimension X of 0.437 inch and a transverse dimension D of 0.312, an axial hole spacing S between the center axes of adjacent holes in the same row of 0.75 inch and a tuft length M that the 55

outer end of the tuft extends radially away from the core of 2.5 inches; while in the tubular brush of example (b) the dimensions corresponding to those set forth above are 0.50 inch, 0.517 inch, 0.368 inch, 1.05 inch and 3.25 inch respectively, and in the tubular brush of example (c) the dimensions corresponding to those set forth above are 0.562 inch, 0.553 inch, 0.346 inch, 1.20 inch, and 4.25 inches respectively. For each of the above examples, the included angle D may be about 10 30°.

What is claimed is:

1. A rotary brush that includes an axially elongated tubular core having a central axis, a cylindrical outer surface and a plurality of spaced tufted holes extending substantially radially relative the core axis, each of said holes being of progressively larger areas in cross sections from the radial inward part of the holes toward the radial outward part of the holes, each hole at the outer surface of the core being of a substantially greater maximum dimension in one direction perpendicular to a radius of the outer surface than the maximum dimension transverse thereto that is perpendicular to said radius.

2. The brush of claim 1 further characterized in that the core is of a unitary integral construction.

3. The brush of claim 1 further characterized in that the first mentioned dimension is at least about 40 percent greater than the transverse dimension.

4. The brush of claim 3 further characterized in that the first mentioned dimension is parallel to the central axis.

5. The brush of claim 4 further characterized in that each hole has a central axis and is of a shape that a plane of the hole central axis that is perpendicular to the tube central axis intersects the tube wall portion defining the hole at parallel lines.

6. A rotary brush that includes an axially elongated brush core having a central axis, a generally cylindrical outer surface and a plurality of spaced tuft holes opening through said outer surface and extending inwardly toward said axis, each of said holes being of a larger cross sectional area at the outer surface than at a location inwardly thereof, each hole at the outer surface of the core being of a substantially greater maximum dimension in one direction perpendicular to a radius of the outer surface than the maximum dimension transverse thereto that is perpendicular to said radius, a tuft extending in each of said holes and means for securing the tufts to said core.

7. The brush of claim 6 further characterized in that the core is of a unitary integral construction and that the first mentioned dimension is parallel to the central axis.
